UNITED STATES PATENT OFFICE.

PAUL M. ZEIDLER, OF NEW YORK, N. Y.

DESIGN FOR A PIANO-CASE.

SPECIFICATION forming part of Design No. 25,898, dated August 4, 1896.

Application filed May 9, 1896. Serial No. 590,947. Term of patent 7 years.

To all whom it may concern:

Be it known that I, PAUL M. ZEIDLER, a citizen of the United States, residing in the city, county, and State of New York, have invented 5 a new and original Design for Piano-Cases, of which the following is a specification.

Figure 1 is a front elevation of one-half of the case; Fig. 2, an end elevation of the same; Fig. 3, a top view of one-half of the case, and 10 Fig. 4 a plan of one end of the case with the cover removed.

The distinguishing feature of my invention consists, primarily, in the simple, Romanesque character of the design as a whole, and, secondarily, in minor details of the design and 15 their arrangement with relation to each other.

In the drawings, A represents the lower frame; B, the key-bed; C, the fall; D, the top frame; E, the swing-desk, and F the lid.

20 One object of my design is the production of a case of plain but imposing appearance, with a broad base and firm support.

As will be seen by reference to Figs. 1 and 2, the toe-pieces a are not only in line with 25 trusses b b, but also project forward nearly as far. It will also be seen that at each end

of the case the toe a, truss b, arm c, and pillars d d' d² are all practically in the same vertical plane—a new and effective arrangement peculiar to my design. The upper columns d² d³ are formed with enlarged fluted centers f f', each of their carved and rounded capitals f' f' being surmounted by a square abacus g, upon which the coping h rests. 30

The coping h and the edges of the cover F 35 conform in general outline to the requirements of the columns d² d³, receding centrally, as at i, and at the corners, as at i' i', coinciding practically with the conformation of the upright parts of the case below. 40

The columns d d', between the trusses b b and toes a a, are also formed with fluted portions j j, and are designed to supplement the upper columns d² d³ in character.

What I claim, and desire to secure by Letters Patent, is— 45

The design for piano-cases herein set forth.

PAUL M. ZEIDLER.
